(57) **CLAIM**

I claim the ornamental design for a bottle, as shown and described.

DESCRIPTION

FIG. 1 is a perspective view of the bottle in accordance with my new design.

FIG. 2 is a top plan view of the bottle in FIG. 1, the bottom of the bottle forming no part of the claimed design.

FIG. 3 is a front elevational view of the bottle in FIGS. 1 and 2.

FIG. 4 is a rear elevational view of the bottle in FIGS. 1-3.

FIG. 5 is a side elevational view of the bottle in FIGS. 1-4, being taken from the left in FIG. 3; and,

FIG. 6 is a side elevational view of the bottle in FIGS. 1-5, being taken from the right in FIG. 3.

The claimed portion of the drawings includes the outside sidewall and the spiraling projections on the inside surface of the bottle. The dash-dash-dash broken lines in the drawings illustrate the portions of the bottle that form no part of the claim. The dash-dash-dash broken line showing of the portion of the inside sidewall surface above, below and between the projections on the inside of the bottle sidewall is not included in the claimed design.

Dash-dot-dash broken lines shown in the drawings represent boundaries of the claimed design and are not part of the claimed design.
